UNITED STATES PATENT OFFICE.

HENRY T. WHITENACK, OF WITT, ILLINOIS, ASSIGNOR OF THREE-FOURTHS TO ROBERT P. BARNARD, OF NOKOMIS, ILLINOIS, AND HUGH WHITENACK AND BERTHA B. KESSINGER, OF WITT, ILLINOIS.

WINDOW-FRAME.

SPECIFICATION forming part of Letters Patent No. 763,234, dated June 21, 1904.

Application filed October 7, 1902. Serial No. 126,365. (No model.)

To all whom it may concern:

Be it known that I, HENRY T. WHITENACK, a citizen of the United States, residing at Witt, in the county of Montgomery and State of Illinois, have invented certain new and useful Improvements in Window-Frames; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

This invention relates particularly to the manner of making the bottom piece or pieces of a window-frame; and the object thereof is to form a weatherproof frame to avoid leaks under the window, which has heretofore been a noticeable and troublesome defect in window-frame construction. In some frames the bottom of the frame has been formed with two pieces, the subsill and the stool or stool-cap for the inside ledge having a narrow inwardly-extending lap-joint just within where the lower sash strikes the subsill. A fault of this construction is that inasmuch as the sash seldom fits perfectly against the sill or because a small obstruction will prevent it resting close rain or snow will drive in under the sash and through the joint to the inside and leak down the inside of the wall, particularly after the wood shrinks or after the stool or sill warps, as it is apt to do. My invention remedies this by making the sill and stool of one piece without the joint mentioned.

In the accompanying drawings, Figure 1 is an elevation of the lower portion of the frame as seen from the outside with the sash partly raised. Fig. 2 is a vertical section, and Fig.

3 is a horizontal section looking down on the sill.

Referring specifically to the drawings, 6 indicates the stool; 7, the subsill; 8, the main sill; 9, the sides; 10, the inside casing; 11, the outside casing, and 12 the lower sash. The main sill is rabbeted at 8° for the clapboard below, and the sides have the usual inside, outside, and parting beads, indicated at 9°. Often the stool and subsill are made of two pieces and have a joint at 6°; but in my invention they are made of one piece, as clearly shown in Fig. 2. Hence rain or snow driving in under the lower sash cannot leak through to the inside, but must flow down the sill to the outside. The main sill extends in under the subsill, as shown, against a rabbet 6°, forming an outwardly-presented shoulder on the under side of the stool, making a wide lap and tight joint with the subsill and stool.

It will be found that a window-frame constructed in the manner above described will exclude wind and storm and is an improvement over the old construction.

What I claim as new, and desire to secure by Letters Patent, is—

In a window-frame, the combination with a main sill, or a stool and subsill formed in one piece and fixed thereon, the subsill having a rabbet in the under side forming an outwardly-presented shoulder against which the main sill fits, and a rabbet in the upper side to receive the sash.

In testimony whereof I affix my signature in presence of two witnesses.

HENRY T. WHITENACK.
